US00D966770S

(12) **United States Design Patent** (10) Patent No.: **US D966,770 S**
Ambrosetti et al. (45) Date of Patent: **** Oct. 18, 2022**

(54) **COFFEE MACHINE**

(71) Applicant: **Solis of Switzerland AG**, Glattbrugg (CH)
(72) Inventors: **Paolo Ambrosetti**, Jerago con orago (IT); **Paolo Marconato**, Saltrio (IT); **Thomas Nauer**, Küsnacht (CH)

(**) Term: **15 Years**

(21) Appl. No.: **35/513,205**

(22) Filed: **Aug. 17, 2021**

(80) **Hague Agreement Data**

Int. Filing Date: **Aug. 17, 2021**
Int. Reg. No.: **DM/216811**
Int. Reg. Date: **Aug. 17, 2021**
Int. Reg. Pub. Date: **Oct. 22, 2021**

(51) **LOC (13) Cl.** **07-02**
(52) **U.S. Cl.**
